UNITED STATES PATENT OFFICE.

EDWARD A. BURBANK, OF BERLIN, NEW HAMPSHIRE.

THAWING APPARATUS.

No. 829,095.

Specification of Letters Patent.

Patented Aug. 21, 1906.

Application filed February 16, 1905. Serial No. 245,814.

To all whom it may concern:

Be it known that I, EDWARD A. BURBANK, a citizen of the United States, residing at Berlin, in the county of Coos and State of New Hampshire, have invented a new and useful Improvement in Thawing Apparatus, of which the following is a full, clear, and exact description, reference being had to the accompanying drawings, forming a part of this specification, in explaining its nature.

The invention relates to means for thawing ice in water and other pipes; and it consists in the following described arrangement and combination of devices for heating a fluid, for forcing the fluid thus heated, and for conducting the heated fluid to the place of use in a water-pipe, the purpose of the invention being to so combine, arrange, and construct the various parts of the apparatus that a simplicity and effectiveness of operation are secured and an economy in manufacture obtained.

I will now describe the invention in conjunction with the drawings, forming a part of this specification, wherein—

Figure 1 is a view in side elevation of my improved thawing apparatus. Fig. 2 is a view, enlarged, in vertical section through the heater. Fig. 3 is a view in vertical section through the drum.

Referring to the drawings, A represents a force-pump mounted upon a base or support a. This pump may be of any desired construction. It is mounted at one end of the base, to which it is permanently secured, and its operating-handle a' extends backward to a convenient point for operation and is connected with the plunger of the pump. The pump preferably draws its supply from a receptacle B, which is connected with the pump by means of the inlet-pipe a², which is preferably flexible and of rubber, and the water is forced from the pump through the outlet or discharge pipe a³, preferably of metal and extending horizontally to the vertical end c of a water-heater C.

An air-chamber D is connected with the pipe a³ at d and so as to provide an air-pressure upon the water column forced through the pipe.

The heater C comprises a burner c' and a coil c² of pipe forming a part of the pipe system of the apparatus. This coil preferably is in two parts or divisions—viz., the outer portion c³ and the inner portion c⁴. The outer is of conical form, reducing in diameter to its

top. The inner portion is contained in the outer and preferably is slightly conical, but in a reverse direction to the outer, being rather larger at the top than at the bottom. 60

The water-supply enters through the pipe c the lower ring of the outer coil. The outer coil connects at its top with the inner coil, and the water-outlet c⁵ is from the lower ring of the inner coil. 65

The coils are contained in a chamber c⁶, formed by a cover or cap c⁷, rising from the circular flange c⁸ of a plate c⁹, mounted upon posts c¹⁰, extending upward from the base a. This cap or cover is removable from the flange c⁸, and it preferably is made non-heat-conducting or of non-heat-conducting material. I have represented it as having an inner shell c¹¹ and outer shell c¹² somewhat larger than the inner shell and inclosing it, 70 forming a chamber c¹³ between them, which is filled with asbestos filling c¹⁴ or other non-heat-conducting material. This chamber and filling extend around the heating-coil and over it, and the cap or cover, with the 75 coil, provides a heating-chamber in three parts—viz., the portion c¹⁵, which is within the inner coil c⁴, the part c¹⁶, which is between the inner coil and the outer coil, and the section c¹⁷, which surrounds the outer coil and 80 is between it and the inner surface of the cap or cover. 85

The cap or cover has one or more vents c¹⁸ through its top. Two are shown. The walls c¹¹ c¹² of the cap or cover come together and 90 are united at the base c¹⁹, where the cap extends upon the flange c⁸.

Any suitable type of burner may be used and any desirable form of liquid fuel. I have represented the employment of a gasolene-gas burner as one being especially well adapted for use under the conditions governing the employment of a thawing apparatus, and it is represented as incorporated in the device by means of the heating-coil E, with which a storage-tank e, containing gasolene, is connected by a supply-pipe e'. From the lower end of the coil E there extends downward the pipe e², which is coupled by the coupling e³ with a horizontal pipe e⁴, in which is the orifice e⁵, through which the gas escapes into the gas-burning chamber e⁶. This chamber is formed by the metal shell e⁷, having the bottom e⁸ and open at its top, and attached to the under surface of the plate c⁹, which plate has an opening e⁹ of very nearly the size of the burning-chamber e⁶ and by which the 95 100 105 110

burning-chamber communicates with the main heating-chamber of the water-heating coil. This burning-chamber e^6 contains the main portion of the pipe e^4 , the coupling e^3 , 5 the gas-heating coil E , and the vertical extension e^2 , and the gas-heating coil is held in the upper part of the chamber over the gas-outlet e^5 , and so that the flame from the burning gas first acts upon the gas-forming coil of 10 the burner and then upon the water-coil. The pipe e^4 extends through the shell e^1 , so that its end e^{10} is accessible and whereby the pipe may be readily removed from the coupling e^3 by being unscrewed therefrom whenever it 15 may be desired to clean the same.

The gasolene-reservoir e is cylindrical in shape and forms the enlarged bearing of the drum F , upon which the flexible pipe f , preferably block-tin, is adapted to be coiled. The 20 drum has the suitable flanges f' f^2 and is mounted with the enlarged reservoir bearing upon the base a by means of the two standards f^3 f^4 , in the upper end of one of which it is journaled. The gasolene-reservoir is adapted to be filled through the inlet e^{11} , closed by a 25 cap. This inlet is arranged in the end e^{12} of the gasolene-reservoir and outside the flange f' of the pipe-drum. The supply-pipe e' extends from the same end of the reservoir to 30 the burner. The reservoir is also provided with a small air-pump e^{13} , largely contained within the reservoir and operated from without the reservoir by the piston-rod e^{14} of a plunger-piston, the outer end of which has a 35 knob e^{15} . Any suitable air-pump may be used, and by its means the gasolene-reservoir e is provided with air under pressure to any desired extent. The reservoir also has preferably at or near the inlet e^{11} an air-vent e^{16} , 40 which is closed by a screw-plug e^{17} . (See Fig. 3.)

The inner end of the flexible pipe F upon the drum is connected with the pipe e^6 , which extends from the lower end of the inner section of the heating-coil, by means of the pipe e^{20} . This pipe e^{20} extends horizontally and then vertically to a position opposite the center of the journal of the drum and then extends horizontally and through the journal 45 to connect with the pipe-section c^{21} , carried by the drum, and connecting with the inner end of the coiled flexible pipe on the drum. This connecting-pipe c^{21} is radial from the surface of the drum to the center of the journal 50 and is then horizontal to the horizontal section of the pipe e^{20} , and the two sections are joined by a coupling which permits the turning of the horizontal section of the part carried by the drum in or on the stationary section of the pipe e^{20} , which extends into the 55 journal. This permits the drum to be turned without interfering with the continuous passage of water from the heater through the connecting-pipe.

60 It will be understood that the gasolene-res-

ervoir is stationary and that the drum turns upon it to permit the uncoiling and coiling of the flexible pipe.

It is usual to employ water as the fluid for melting the ice in the water or other pipe; but 70 any other fluid capable of conducting heat may be employed. The course of the water is through the pump A , the pipe a^3 connecting it with the heating-coil, the sections of the heating-coil, the pipe c^{20} , and the flexible 75 coil extending about and from the drum into the water-pipe.

The pump provides the main pressure. The air-chamber D takes a portion of this pressure and makes it constant, so that the hot 80 water leaves the discharge end of the flexible pipe in a continuous stream.

The reservoir e preferably is supported at its inner end by the standard f^4 by means of the inward extension or bearing f^5 , which enters a receiving-chamber f^6 in the inner end 85 of the reservoir shell or case.

The drum F is mounted upon the base a at the end opposite that upon which the pump A is mounted, and the burner and water-heater are together mounted upon the base a 90 at about the center of its length and between the pump and the drum.

The pipe c^{20} is provided with a outlet-cock c^{22} , by means of which the burner and pipe 95 may be drained, and the gasolene-feed pipe e' has a controlling-valve e^{18} .

The means for operating the apparatus are so located that the pumping of the water and the control of the burner and of the gasolene-feed may be effected from the same side of the device. The operation of the apparatus has been described in connection with the description of its construction.

The water-heating apparatus is such that 105 the water is gradually heated as it enters the coil and leaves the heater at its highest or greatest heating-point, and the form of the gas-burner and of the coil described provides for the very quick and high heating of the 110 passing water and is one of the principal features of my invention.

It will be understood that the fluid-fuel receptacle is removable from the cavity of the drum, and this is preferably accomplished by 115 releasing the stand which supports its outer end from the base, when the receptacle and stand may be moved together from the drum.

Having thus fully described my invention, I claim and desire to secure by Letters Patent of the United States—

1. In an ice-thawing apparatus of the character specified, the combination of a fluid-forcing means, a hollow drum, a hollow bearing therefor, a stand for supporting said bearing, a flexible pipe adapted to be wound on said drum, one end of which has a swiveling connection with a supply-pipe extending through said hollow bearing, a pipe system 125 extending from said fluid-forcing means and 130

connecting with said supply-pipe, a water-heater in said pipe system, a burner, a fluid-fuel receptacle contained in the cavity of said drum and forming in part a bearing therefor, 5 said receptacle being removable from said drum and connecting with said burner, and a standard for supporting the outer end of said receptacle.

2. In an ice-thawing apparatus of the character specified, the combination of a fluid-forcing pump, a hollow rotatable drum, a hollow bearing therefor, means of support for said bearing, a flexible pipe adapted to be wound on said drum, a pipe system extending 10 from said pump and making connection with said pipe on the drum by a connection extending through the hollow bearing thereof, a water-heater in said pipe system, a burner for said water-heater, a fluid-fuel receptacle contained in the cavity of the drum and connecting with said burner, which receptacle forms one of the bearings for the drum, and a stand for supporting one end of said receptacle.

25 3. In an ice-thawing apparatus of the character specified, the combination of a fluid-forcing pump, a hollow rotatable drum open at one end, a hollow bearing at the other end of said drum, means of support therefor, a flexible pipe adapted to be wound on said drum, a pipe system extending from said pump and making connection with said pipe on the drum by a connection extending through the hollow bearing thereof, a water-heater in said pipe system, a burner for said water-heater, a fluid-fuel receptacle contained in the cavity of the drum and connecting with said burner, a removable stand 30 for supporting the outer end of said receptacle, and a support for the same inside the drum.

40 4. In an ice-thawing apparatus of the character specified,

acter specified, the combination of a fluid-forcing pump, a hollow rotatable drum open at one end, a hollow bearing for the other end thereof, means of support therefor, a flexible pipe adapted to be wound on said drum, a pipe system extending from said pump and making connection with said pipe on the drum by a connection extending through the hollow bearing thereof, a water-heater in said pipe system, a burner for said water-heater, a fluid-fuel receptacle contained in the cavity of the drum and connecting with said burner, one end of said receptacle being exposed and it providing in part a bearing for said drum, means for supporting said receptacle, and an air-forcing pump mounted upon the exposed end thereof.

5. In an ice-thawing apparatus of the character specified, the combination of a fluid-forcing pump, a hollow rotatable drum open at one end, a hollow bearing at the other end thereof, a support for said bearing, a flexible pipe adapted to be wound on said drum, a pipe system extending from said pump and making connection with said pipe on the drum through the hollow bearing thereof, a water-heating coil in said pipe system, a burner for said water-heater, a fluid-fuel receptacle contained in the cavity of the drum, having a head at one end, a stand for supporting said receptacle in a stationary position whereby said receptacle may form in part a bearing for said drum, inlet and outlet 60 pipes to said receptacle, said outlet-pipe connecting with said burner, an air-forcing pump mounted upon said receptacle in an accessible position.

EDWARD A. BURBANK.
